WILLARD R. WALKER, OF SYRACUSE, NEW YORK

DISHWASHING MACHINE

Application filed May 1, 1929. Serial No. 359,563.

This invention relates to a dishwashing machine of the class set forth in my Patent No. 1,724,383, August 13, 1929, in which the washing fluid is impelled upwardly through open mesh dish-supporting trays or baskets within a suitable vat, the impeller being directly connected to and actuated by a suitable motor at the underside of the bottom of the vat.

One of the objects is to establish a relatively short direct connection between the impeller and motor so that the impeller may be driven at the same rate of speed as the revolving part of the motor with a minimum torque and at the same time to place the motor and impeller into more compact relation and more nearly in the same horizontal plane than has heretofore been practiced.

Another object is to suspend the motor directly from the bottom of the vat and in such manner that the vibration of the motor and bottom of the vat incidental to the operation of the motor and impeller will be reduced to a minimum.

In other words, I have sought to establish a relatively broad area of contact, both horizontally and vertically, between the motor case and bottom of the vat by tapering the upper end of the motor case or its supporting frame and nesting said tapered end in a complementary tapered socket or recess in the bottom of the vat so that the contiguous parts may reinforce and brace each other against vertical or lateral vibration.

A further object is to provide the bottom of the vat with an upwardly tapered center portion and an upwardly flaring outer portion integrally united to each other at their junctions around the outside of the motor case to not only form an annular trough in which the impeller is rotatable but also to brace the internal upwardly tapered portion which supports the motor against lateral vibration.

Another object is to provide the outer upwardly flaring portion of the bottom of the vat with a valve-controlled drainage outlet section having overflow means limiting the volume of water within the vat to a predetermined level below the apex of the central upwardly tapered portion of the bottom.

Another object is to provide this drainage

and overflow section with means for indicating the level of the water within the vat.

A further object is to provide the outer upwardly flaring portion of the bottom of the vat with a valve-controlled water inlet entering the vat at a level slightly above the level of the overflow passage.

Other objects and uses relating to specific parts of the machine will be brought out in the following description.

In the drawings:—

Figure 1 is a side elevation of a mechanical dishwasher embodying the various features of my invention.

Figure 2 is an enlarged horizontal sectional view taken in the plane of line 2—2, Figure 1.

Figure 3 is a detail vertical sectional view taken in the plane of line 3—3, Figure 2.

Figure 4 is a detail sectional view taken in the plane of line 4—4, Figure 3.

Figure 5 is a detail sectional view taken in the plane of line 5—5, Figure 4.

Figure 6 is an enlarged detail sectional view taken in the plane of line 6—6, Figure 4.

Figures 7 and 8 are enlarged detail vertical sectional views taken in the planes of lines 7—7 and 8—8, Figure 2.

Figure 9 is a detail horizontal sectional view taken in the plane of line 9—9, Figure 3.

Figure 10 is a side elevation of the detached impeller shown in top plan in Figure 2.

As illustrated, this machine comprises an upright cylindrical vat 1 of sheet metal or other suitable material having its upper end provided with a lid 2 and its bottom provided with a central upwardly tapered or conical portion 3 and an outer upwardly flaring portion 4 integrally united to the lower marginal edge of the tapered portion 3 and its outer marginal edge secured to the peripheral walls of the vat to form a watertight joint therewith thereby forming an annular trough 5 in which the impeller, presently described, is rotatable.

The angle of the vertex of the central upwardly tapered portion 3 is less than ninety degrees so that the angle between its inclined sides and axis is less than forty-five degrees,

the object being to afford a relatively sturdy and self-stiffening support for an electric motor as 6.

The upward taper of the central portion 3 of the bottom of the vat forms a correspondingly upwardly tapered or conical recess 7 in which the motor supporting frame or case is nested.

That is, the motor case is provided with an upwardly tapered extension or supporting frame 8 complementary to the taper of the recess 7 in which it is seated or nested to firmly engage the inner surface of the conical portion 3 and thereby to firmly support the motor coaxial with the axis of the vat.

The apex of the conical portion 3 is substantially flat and horizontal to be engaged by the apex of the motor supporting frame 8 and also by a nut 9, Figure 3.

20 A bushing 10 has its lower end flanged outwardly and engaged with an internal flange 11 of the motor supporting frame 8, said bushing being extended through registering openings in the upper end of the motor case 8 and apex of the conical portion 3 and having its upper end threaded and engaged by the nut 9 so that when the nut is tightened it will draw the upper end or apex of the frame 8 against the underside of the apex of the conical portion 3 while the nut 9 will engage the upper surface of the apex of said conical portion 3.

It is now evident that the entire motor is suspended from the apex of the conical portion 3 through the medium of the bushing 10 and nut 11 and that the motor may be removed by the simple operation of loosening the nut 9 or reversely replaced by the tightening of this nut, it being understood that the engagement of the upwardly tapered portion of the frame 8 with the correspondingly tapered portion 3 of the bottom of the vat serves to hold the motor and also the adjacent portions of the bottom of the vat against lateral or vertical vibration and that the strains due to the weight of the motor on the conical portion 3, is transmitted more or less to the peripheral walls of the vat through the medium of the upwardly flaring portion 4 of the bottom.

This construction is particularly sturdy and enables the motor to be brought close to the impeller thereby greatly reducing the torque upon the motor shaft.

55 The motor is provided with a relatively short vertical shaft 12 extending through a central opening in the bushing 10 and nut 9 and upwardly beyond said nut for receiving and supporting a rotary impeller 13.

10 The upper end of the shaft 12 extends into a socket 14 in the lower end of the hub of the impeller and is preferably corrugated at 15 for interlocking engagement with similar corrugations in the walls of the socket 14 for establishing spline connections between the

shaft and impeller for rotating the latter, the upper end of the hub of the impeller being closed across the top of the shaft 12 to reduce the liability of leakage of the water from the interior of the vat along said shaft.

70 It will be evident, however, that the firm engagement and close fitting of the upper end of the frame 8 and nut 9 against the lower and upper faces of the apex of the conical portion 3 further reduces the liability of leakage of water from the interior of the vat downwardly along the shaft.

75 The bushing 10 may form a part of the upper end 8 of the motor which is provided with an oil-containing chamber 16 communicating with the interior of the bushing 10 through suitable passages 17, Figure 3, for lubricating the shaft.

80 The hub of the impeller 13 is provided with a downwardly flaring skirt 13' extending along the peripheral wall of the conical portion 3 but in spaced relation thereto to avoid friction therewith as the impeller is rotated.

85 A pair of similar but reversely arranged impeller blades 13'' are secured to the periphery of the lower or larger end of the skirt 13' and are of special construction to enable the water to be thrown upwardly through the dish-supporting trays with considerable force and with a minimum power as will be hereinafter more fully described.

90 The outer upwardly flaring bottom portion 4 is provided near its junction with the lower end of the conical portion 3 with a drainage outlet 18 surrounded by a downwardly extending flange 19 registering with a similar opening in the upper end of a combined drainage and overflow shell 20 preferably of cast metal.

95 The upper end of the shell 20 extends from the bottom of the conical portion 3 to the periphery of the outwardly and upwardly flaring bottom portion 4 and is secured to the underside thereof and to the peripheral wall of the vat by screws or bolts 21, Figure 2, 100 and 21', Figure 4.

105 That is, the flange 19 is preferably formed upon a separate ring 19' which is secured to the upper face of the adjacent portion of the bottom of the vat by the screws 21, see Figures 4 and 7.

110 This casting 20 is mainly hollow and extends downwardly from the bottom portion 4 to about the level of the bottom of the motor 6 and is provided with a reduced lower end having a drainage outlet conduit 22 adapted to be connected to any available soil pipe, not shown.

115 The upper end of the casting extends laterally and upwardly some distance beyond the drainage opening 18 and is provided with an outwardly and upwardly inclined partition 23 dividing the interior of the casting into upper and lower chambers 24 and 24', the outer portions of said chambers being 120

125

130

connected by an overflow passage 25 adjacent the outer wall of the casting but in a plane some distance above the drainage opening 18 for limiting the volume of water within the vat to be operated upon by the impeller 13.

The partition 23 is provided with a drainage opening 26 beneath and aligned with the drainage opening 18 in the bottom of the vat and controlled by a valve 27 which is operable at will in a manner presently described.

When the valve is closed and the washing fluid is introduced into the vat it will flow through the opening 18 into the upper chamber until it reaches the level of the overflow 25 or some distance above the bottom of the trough 5 at which time it will overflow into the chamber 24' and thence outwardly through the drainage outlet 22 thereby limiting the quantity of the washing fluid within the vat to a relatively small volume which is found to be most efficient in machines of this character not only for washing purposes but also for conserving the use of the water and power required for projecting the same upwardly through the dish-supporting trays or baskets.

On the other hand, when it is desired to drain the water from the vat it is simply necessary to open the valve 27 thereby permitting the water to pass directly from the trough 5 through the openings 18 and 26 and thence downwardly and outwardly through the chamber 24' and drainage outlet 22.

The valve 27 is preferably of the butterfly type and is arranged to open downwardly and laterally with the water pressure from within the vat and to close against a suitable seat 28 consisting in this instance of a brass or equivalent annular ring or bushing which is secured to the walls of the opening 26.

As illustrated, the lower side of the valve 27 is provided with pendant lugs pivoted at 29 to a suitable lever 30 which, in turn, is secured to a rock shaft 31 at one side of the opening 26 with its axis in substantially the same plane as the valve seat 28, the pivotal connection 29 between the valve 27 and lever 30 permitting the valve to automatically adjust itself to its seat. The rock shaft 31 is journaled in suitable bearings 32 in the adjacent portion of the casting 20 to form water-tight joints therewith, see Figure 4.

The outer end of the shaft 31 extends through and beyond the adjacent portion of the casting 20 and is secured to one arm of a U-shaped yoke 33 having its other arm secured to a coaxial operating shaft 34 which extends through a suitable bushing 35 in the adjacent portion of the peripheral wall of a skirt extension 1' of the vat 1 and has its outer end provided with a handle 36 by which it may be operated.

The yoke 33 extends radially from the shaft sections 31 and 34 and constitutes what may

be termed a crank arm carrying a crank pin 37 to which is connected one end of a coiled spring 38 having its other end attached to an anchoring pin or stud 39.

The crank pin 37 and stud 39 are located at opposite sides of the axis of the shaft sections 31 and 34 while the spring 38 is aligned with the space between the opposite arms of the yoke 33 and is movable with the yoke 33 about the axis of the anchor pin 39 to opposite sides of the axis of the shaft sections 31 and 34 for yieldingly holding the yoke 33 in its valve-closing position as shown by full lines in Figure 6 and in its valve-opening position as shown by dotted lines in the same figure. That is, when the valve 36 is in its normal valve-closing position, the spring 38 will hold the valve in that position against the water pressure within the vat but when the operating member 36 is turned to open the valve the spring 38 will pass to the opposite side of the axis of the shafts 31 and 34 to yieldingly hold the valve in its open position wholly at one side of the axis of the drainage openings 18 and 26, as shown by dotted lines in Figure 5.

The cylindrical skirt or extension 1' of the vat is rigidly secured at its upper end to the lower end of the vat to extend downwardly therefrom to about the level of the lower ends of the motor 6 and casting 20 for concealing and protecting the latter and also to form a convenient means for supporting the vat upon a suitable frame or legs 1" shown in Figure 1 and partly in Figure 3.

The outer wall of the upper chamber 24 is provided with an opening 40 at one side of the overflow passage 25, Figure 4, for receiving the inner end of a sight tube 41 having its outer end extended through an opening in the skirt 1' and provided with a transparent closure 42 which is held in place by a suitable cap nut 43 to enable the user to visualize the level of the liquid within the vat, the tube 41 being inclined outwardly and upwardly at substantially the same inclination as the partition 23 so that its outer end will be at about the same level as the overflow passage 25.

Under these conditions when the water in the bottom of the vat 1 reaches the level of the overflow 25 it will also flow into the sight tube 41 and be visible through the transparent closure 42 thereby indicating to the operator that the water supply should be shut off to conserve the water.

The upwardly flaring bottom portion 4 of the vat 1 is provided near its outer marginal edge with an opening 44, Figure 8, surrounded by a downwardly tapered flange 45 in which is seated the upper end of a water inlet nipple 46 having an annular downwardly tapered flange 47 fitting snugly within the flange 45 to form a water-tight joint therewith, said nipple being provided with

an inwardly projecting deflector 47' for deflecting the water inwardly toward the center of the vat and preventing its direct upward passage.

- 5 The lower end of the nipple is connected to a water supply pipe 48 leading from any available source of supply and provided with a self-closing valve 49 having an operating handle 50 which is yieldingly held in its valve 10 closing position by a coiled spring 51, Figure 8, thus making it necessary to hold the valve open by hand until the required volume of water is supplied to the interior of the vat which further reduces the liability of wasting 15 of the water.

The electric motor 6 may be connected to a source of current supply in any suitable manner not necessary to herein illustrate or describe except that the current may be controlled by a suitable switch 52 mounted on the side of the skirt 1' adjacent the controls 36 and 50, Figures 1 and 2.

As previously stated, the impeller blades 13" are mounted upon the lower end of the 25 conical skirt 13' at diametrically opposite sides thereof to extend circumferentially in reverse directions substantially concentric with the axis of the impeller and in slightly spaced relation to the periphery of the conical 30 part 13' so as to allow passage of the water through the intervening spaces when the impeller is in action and thereby to avoid over-loading the blades with water.

The ends of the blades facing the direction 35 of rotation are substantially horizontal circumferentially but are inclined outwardly and upwardly radially so as to pick up the water with a minimum resistance, the remaining portion of the blade being gradually 40 inclined upwardly circumferentially at a gradually increasing angle to a horizontal and are also curved outwardly and upwardly radially at a gradually increasing angle, the object of which is to confine the water within 45 the inner and outer edges of the blades as much as possible against centrifugal throw and at the same time to impart to the water therein an upward movement with sufficient force to carry it thru the superposed dish-supporting trays and against the dishes 50 therein.

The impeller is in this instance adapted to be rotated in a counter-clockwise direction when viewed from the top and owing to the 55 peculiar construction of the blades it is evident that the water will be picked up by both blades and gradually raised with an accelerated motion sufficient to impel the water to the top of the vat with a more or less whirling motion thereby passing upwardly through the dish-supporting trays and against the dishes therein and returning to the bottom of the vat by its own gravity to effect the washing of the dishes by the upward current and 60 also by the downward current, it being under-

stood that the outward and upward curvature of the impeller blades tends to retain the water thereon against undue displacement therefrom by centrifugal force.

That is, during the operation of the impeller under relatively high speed corresponding to the speed of the motor the tendency is to displace the relatively small body of water from the center toward the circumference of the vat but in order to further reduce this 70 centrifugal swirling of the water I have provided a series of baffle plates 53 arranged in uniformly spaced relation circumferentially around the outside of the path of movement 75 of the impeller blades 13" and in planes substantially tangential to the lower end of the conical impeller shell 13' as shown more clearly in Figures 2 and 3.

The outer ends of these baffle plates are secured to an outer ring 54 within the bottom of the vat close to the periphery thereof while their inner ends 53' are reduced in vertical height and extended over and above the path of movement of the impeller blades 13" and are secured to an inner ring 55 surrounding 80 the outer end of the hub of the impeller, as shown more clearly in Figure 3, the extensions 53' being substantially radial to the axis of the impeller, and also arranged in uniformly spaced relation circumferentially, as shown in 85 Figure 2.

The upper edges of the baffle plates 53 are substantially horizontal but the lower edges of the outer wider portions are inclined at substantially the same angle as the upwardly flaring bottom portion 4 of the vat but in 90 slightly spaced relation thereto with their inner edges substantially vertical and close to the path of travel of the outer edges of the impeller blades.

It, therefore, follows that when the impeller is rotated at a relatively high rate of speed it will tend to throw the water outwardly from the center toward the circumference by centrifugal force but this tendency will be overcome by the baffle plates 53 which receive the impact of the water and serve to deflect the latter upwardly to aid the impeller blades in projecting the water through the superposed dish-supporting trays 105 and against the dishes therein.

It is now evident that the relatively small body of water is impelled upwardly by two forces, first, by the impeller blades 13" and, second, by the impact of the whirling water 110 against the baffle plates 53 and that this upward deflection by both forces is substantially uniform throughout the horizontal area of the interior of the vat causing the water to impinge against the dishes in the open work trays with approximately uniform velocity and with more or less glancing impact, both upon the upward movements and also upon the return downward movements of the water, resulting in a thorough and expeditious 115

cleansing of the dishes with the expenditure of a minimum amount of electric current and water.

The outer and inner rings 54 and 55, together with the deflector plates 53 carried thereby, are removably supported within the vat upon a plurality of ledges 56 which are arranged in uniformly spaced relation circumferentially and are soldered or otherwise 5
permanently secured to the walls of the vat 10 near the junction of the cylindrical portions with the marginal edge of the bottom portion 4, as shown more clearly in Figures 2 and 3. A woven wire shield 57 carried by a suitable 15 supporting ring 58 is removably mounted upon the upper edges of the baffle plates 53 in a substantially horizontal position to prevent the passage of knives, forks, spoons and similar articles therethrough, which might 20 otherwise interfere with or impair the use of the impeller.

Operation

The dish-supporting trays, not shown, but 25 commonly used in washing machines of this type, with the dishes therein, are supported in any suitable manner within the vat 1 some distance above the path of movement of the impeller 13.

The valve 49 is then opened by hand and held open to permit the inflow of the washing 20 fluid into the vat until it reaches the level of the overflow 25, as visually indicated through the sight tube 41 at which time the overflow 25 will limit the height of the water as indicated by the dotted line —a— in Figure 3.

It will be observed that the level of the overflow passage 25 is some distance below the apex of the central conical portion 3 and also in a plane below the outer marginal edge 25 of the upwardly flaring bottom portion 4 which assures the retention of a relatively small volume of water within the vat in which the impeller blades 13" are movable thereby not only conserving the use of water but also reducing to a minimum the power required for the operation of the impeller, it being understood that the valve 49 is permitted to close as soon as the height of the water in the vat reaches the level of the overflow.

When the water within the vat has reached a maximum level as determined by the overflow 25 the motor switch 52 will be closed to start the motor for rotating the impeller counter-clockwise.

This rotation of the impeller causes its blades 13" to throw the water upwardly through and above the dish-supporting trays with a more or less centrifugal motion. This centrifugal motion of the water is counteracted partially by the upward and outward inclination of the blades 13" and partially by impact against the baffle plates 53 which further tends to deflect the water upwardly through the dish-supporting trays and

against the dishes therein, this impact of the water against the dishes occurring during the upward projection of the water through the dish-supporting trays and also by the return of the water from the top downwardly to the bottom of the vat for recirculation by the impeller. 70

This washing operation requires only a relatively short period of time and when completed the valve 27 may be opened to allow the discharge of the water from the vat through the drainage conduit 22. If it is desired to rinse the dishes after the washing operation the valve 27 may be again closed and the inlet valve 49 opened to allow the impeller to again circulate the water upwardly through the dish-supporting trays for rinsing purposes followed by the opening of the valve 27 to drain the rinsing water from the vat leaving the supporting trays for the rinsed dishes within the vat to drain until dry, if desired, thus completing the washing, rinsing and drying operations. 80

I claim:

1. In a dishwashing machine, a vat having 90 a central upwardly tapered recess in its bottom, and a motor-supporting frame having its upper end tapered to correspond to the taper of the recess and seated therein.

2. In a dishwashing machine, a vat having 95 its bottom provided with an upwardly tapered central portion and an outer upwardly flaring portion united to the lower marginal edge of the central portion to form an annular trough, a motor suspended from the apex of said central portion and provided with a shaft extending through an opening in said apex, and an impeller mounted on the upper end of the shaft to rotate therewith in said trough, the angle of the vertex of the 100 central tapered portion being not to exceed ninety degrees.

3. In a dishwashing machine, a vat having 110 a central upwardly tapered recess in its bottom, and a motor-supporting frame having its upper end seated in said recess, the vertex of the tapered recess forming an acute angle.

4. In a mechanical dishwasher, a shaft having 115 its bottom provided with an upwardly tapered central portion and an upwardly flaring outer portion united to the lower marginal edge of the central tapered portion, a motor having a case provided with a tapered upper end seated within and against the upwardly tapered central portion and provided with an extension projecting through an opening in the apex of said central tapered portion, a nut engaging the upper end of said extension and upper surface of said apex, said motor having a shaft extending upwardly through an opening in the nut, and an impeller mounted on the upper end of the shaft to rotate therewith and provided with a downwardly flaring skirt carrying the impeller blades rotatable in said trough. 120 125 130 135

5. In a mechanical dishwasher, a vat having its bottom provided with a central upwardly tapered portion and an upwardly flaring outer portion united to the lower marginal edge of the central portion to form an annular trough, said upwardly flaring portion having a drainage outlet near its junction with the central tapered portion, a drainage conduit having its upper end secured to the underside of said upwardly flaring portion around the drainage outlet, a partition dividing the interior of the drainage conduit into lower and upper compartments, the upper compartment having an overflow passage in a plane some distance above the drainage outlet and discharging into the lower compartment, said partition having a drainage opening communicating with the first-named drainage outlet, and a valve operable at will for controlling the second-named drainage opening. 85
6. In a mechanical dishwasher, a vat having its bottom provided with an upwardly tapered central portion forming a correspondingly tapered recess in its underside, a motor seated in said recess and provided with a shaft extending through an opening in the apex of said tapered portion and an impeller mounted on the upper end of the shaft within the vat and provided with a downwardly flaring skirt having impeller blades secured to its lower marginal edge. 95
7. In a mechanical dishwasher having its bottom provided with an upwardly tapered central portion and an upwardly flaring outer portion united to the lower edge of the central tapered portion to form an annular trough, a motor secured within the upwardly tapered central portion and provided with a shaft extending through an opening in the apex thereof, an impeller mounted on the upper end of the shaft to rotate therewith and provided with a downwardly flaring skirt surrounding said central tapered portion and having its lower marginal edge provided with impeller blades movable in said trough, and a series of baffle plates within the vat having portions extended beyond the path of movement of the impeller blades and their lower edges adjacent and substantially parallel with the upwardly flaring outer portion of the bottom of the vat. 105
8. In a mechanical dishwasher having its bottom provided with an upwardly tapered central portion and an upwardly flaring outer portion united to the lower edge of the central tapered portion to form an annular trough, a motor secured within the upwardly tapered central portion and provided with a shaft extending through an opening in the apex thereof, an impeller mounted on the upper end of the shaft to rotate therewith and provided with a downwardly flaring skirt surrounding said central tapered portion and having its lower marginal edge provided with impeller blades movable in said trough, and a series of baffle plates within the vat having portions extended beyond the path of movement of the impeller blades and their lower edges adjacent and substantially parallel with the upwardly flaring outer portion of the bottom of the vat. 115
9. In a mechanical dishwasher having its bottom provided with an upwardly tapered central portion and an upwardly flaring outer portion united to the lower edge of the central tapered portion to form an annular trough, a motor secured within the upwardly tapered central portion and provided with a shaft extending through an opening in the apex thereof, an impeller mounted on the upper end of the shaft to rotate therewith and provided with a downwardly flaring skirt surrounding said central tapered portion and having its lower marginal edge provided with impeller blades movable in said trough, and a series of baffle plates within the vat having portions extended beyond the path of movement of the impeller blades and their lower edges adjacent and substantially parallel with the upwardly flaring outer portion of the bottom of the vat. 125
10. In a mechanical dishwasher having its bottom provided with an upwardly tapered central portion and an upwardly flaring outer portion united to the lower edge of the central tapered portion to form an annular trough, a motor secured within the upwardly tapered central portion and provided with a shaft extending through an opening in the apex thereof, an impeller mounted on the upper end of the shaft to rotate therewith and provided with a downwardly flaring skirt surrounding said central tapered portion and having its lower marginal edge provided with impeller blades movable in said trough, and a series of baffle plates within the vat having portions extended beyond the path of movement of the impeller blades and their lower edges adjacent and substantially parallel with the upwardly flaring outer portion of the bottom of the vat. 130

impeller blades movable in said trough, and a series of baffle plates within the vat having portions extended beyond the path of movement of the impeller blades and their lower edges adjacent and substantially parallel with the upwardly flaring outer portion of the bottom of the vat, said portions of the baffle plates being disposed in uniformly spaced relation circumferentially of and substantially tangential to the skirt of the impeller. 75

In witness whereof I have hereunto set my hand this 10th day of April, 1929.

WILLARD R. WALKER.
